[57] CLAIM

The ornamental design for a comb, as shown and described.

DESCRIPTION

FIG. 1 is a front elevation of a comb, showing my new design, the opposite side being a mirror image;

FIG. 2 is a top plan view;

FIG. 3 is a bottom plan view;

FIG. 4 is a left side elevation taken from the left of FIG. 1;

FIG. 5 is a right side elevation taken from the right of FIG. 1;

FIG. 6 is a front elevation of a comb showing a modified form of my new design;

FIG. 7 is a top plan view of FIG. 6;

FIG. 8 is a bottom plan view of FIG. 6;

FIG. 9 is a left side elevation taken from the left of FIG. 6;

FIG. 10 is a right side elevation taken from the right of FIG. 6;

FIG. 11 is a front plan view of a first modified form of my new comb;

FIG. 12 is a top plan view taken from FIG. 11;

FIG. 13 is a bottom plan view of FIG. 11;

FIG. 14 is a left side elevation taken from the left of FIG. 11;

FIG. 15 is a right side elevation taken from the right of FIG. 11;

FIG. 16 is a front elevation of a comb showing a third modified form of my new design;

FIG. 17 is a top plan view of FIG. 16;

FIG. 18 is a bottom plan view of FIG. 16;

FIG. 19 is a left side elevation taken from the left of FIG. 16;

FIG. 20 is a right side elevation taken from the right of FIG. 16;

FIG. 21 is a front elevation of a comb showing a fourth modified form of my new design;

FIG. 22 is a top plan view of FIG. 21;

FIG. 23 is a bottom plan view of FIG. 21;

FIG. 24 is a left side elevation taken from the left of FIG. 21;

FIG. 25 is a right side elevation taken from the right of FIG. 21.
